UNITED STATES PATENT OFFICE.

MORRIS SCHLEPP, OF NEW YORK, N. Y.

DESIGN FOR A GLOBE-HOLDING ELECTRIC FIXTURE.

Application filed March 14, 1928. Serial No. 25,844. Term of patent 7 years.

To all whom it may concern:

Be it known that I, MORRIS SCHLEPP, a citizen of the United States, and a resident of New York city, in the county of New York and State of New York, have invented a new, original, and ornamental Design for a Globe-Holding Electric Fixture, of which the following is a specification.

Reference is had to the accompanying drawing forming part thereof, wherein—

Fig. 1 is a top plan view of a globe holding electric fixture showing my new design.

Fig. 2 is a side elevational view thereof.

Fig. 3 is a bottom plan view thereof.

I claim:

The ornamental design for a globe holding electric fixture substantially as shown.

Signed at New York, in the county of New York and State of New York this 12th day of March A. D. 1928.

MORRIS SCHLEPP.
